JOHN D. IHLDER, OF NEW YORK, N. Y., ASSIGNOR TO OTIS ELEVATOR COMPANY, OF EAST ORANGE, NEW JERSEY, A CORPORATION OF NEW JERSEY.

ELEVATOR-CONTROL SYSTEM.

No. 820,498.

Specification of Letters Patent.

Patented May 15, 1906.

Application filed February 16, 1905. Serial No. 245,964.

To all whom it may concern:

Be it known that I, JOHN D. IHLDER, a citizen of the United States, residing at New York city, in the county of New York and State of New York, have invented certain new and useful Improvements in Elevator-Control Systems, of which the following is a specification.

My invention relates to elevator-control systems, and more particularly that type of electric elevator which is set in motion by pushing a button and whose subsequent operation—that of accelerating, slowing down, and finally stopping it—is entirely automatic.

One of the objects of this invention is to provide means for automatically stopping an elevator-car at any predetermined point in its travel regardless of its load, direction of travel, or speed, or whether said car is ascending or descending.

A further object of my invention is the provision of means for automatically reducing the speed of an elevator-car and varying such reduction of speed in accordance with the load to stop the car substantially level with any desired floor.

Other objects of the present invention will appear hereinafter, the novel combinations of elements being pointed out in the claims.

In the accompanying drawing I have shown diagrammatically an electric elevator-control system for four floors or landings. The hoisting mechanism itself is not shown, as that may be of any desired construction and forms no part of the present invention.

Referring to the drawing, 10 designates an elevator-car, upon which are mounted the push-buttons 11, 12, 13, 14, and 15.

20, 21, 22, and 23 are push-buttons located at or near the various landings.

30, 31, 32, and 33 designate contacts at the various landings, which are arranged to break the circuit through conductor 34 whenever one of the elevator hatchway-doors is opened.

45 The floor relays or magnets are shown at 40, 41, 42, and 43.

44 designates a safety car-magnet, and 45 is a double-wound magnet, the purpose of which is to prevent interference between the

50 various buttons.

46 is a magnet which controls the circuit of an accelerating-magnet 50.

80 is the accelerating or starting resistance for the motor.

60 represents an electromagnetic brake, 55 and 70 is what I call the "load-magnet."

65 designates a magnet which controls a circuit through the resistance 90 and extra field 91, and 16 is a magnet which controls the circuit to the load-magnet 70.

92 designates the shunt-field, 93 the series field of the motor, while 94 is its armature.

95 and 96 are armature-brushes.

97 is a magnet which controls the circuit feeding the various car and landing push-buttons.

98 is a resistance which may be used, connected in series with the magnet 97.

100 and 200 designate reversing-switches, which, among other things, control the direction of rotation of the hoisting-motor.

110, 111, 112, and 113 are the various limit-switches, which are usually placed on the hoisting-machine or in the hatchway and operate to interrupt the supply of current to the system at predetermined points of the car travel.

120 designates what I call the "floor-controller," an object of which, among other things, is to control the various operating-circuits in such manner as to automatically stop the elevator-car level with the various floors or landings regardless of the load which the car may be carrying at the time and the speed which it may have attained during its travel.

I will now go into a more detailed description of my device, showing the various circuits and how they act on the different parts to produce the desired results.

The source of electrical supply is designated by the characters + and -. The current-supply for the operating-circuits is taken from the + main by wire 38. This wire is connected to the contact 37, against which the contact 36 is held by the spring 35, provided the magnet 97 is not energized. From here the circuit is led by wire 34 through the door-contacts 33, 32, 31, and 30 to the safety push-button 11, located in the car. This safety-button is what is known as a "closed-circuit" button—that is, the circuit through the button is normally closed and is broken only when the button is operated. From the button 11 the wire 39 leads to one terminal of the coil 46' of the magnet 45. The other terminal of coil 46' is connected to one terminal of coil 47 and wire

48. These two coils 46' and 47 are wound in opposition to each other, so that when current is traversing both coils at the same time one of them tends to neutralize the effect of the other. The other terminal of 47 is connected to the contact 49. This contact is held normally in contact with 51 by the spring 52, but is arranged to be separated from it when the magnet 45 is energized, thus 50 breaking the connection between contacts 49 and 51. Contact 51 is connected by wire 53 to the movable contact 54, which in the position shown in the drawing is in contact with a stationary contact 55. This latter 55 contact is connected by wire 56 to the four landing push-buttons 23, 22, 21, and 20. These four buttons are what is known as "open-circuit" buttons. Having traced the circuits so far, it is apparent that the operating-circuit is open at the landing-buttons 23, 22, 21, and 20. In order, therefore, to follow the circuit further, suppose the button 23 be pushed. This puts 24 and 25 into electrical contact and by wire 26 furnishes a path for 60 the current to one terminal of the floor-magnet 40. The other terminal of the magnet 40 leads to the floor-controller 120 by wire 121. This floor-controller 120 comprises a number of contact-strips—such as 1, 2, 3, 4, 5, 6, 7, and 8—rigidly mounted on a base of insulating material, such as slate, which may be mechanically connected to some moving part of the elevator machinery, such as the winding-drum shaft. Thus the insulating- 70 base, together with the contact-strips mounted thereon, will be revolved as the elevator machinery is in motion. Adjacent to the path of these contact-strips and so arranged as to make contact with them are fixed contacts, to which electrical conductors are connected. On the drawing I have shown twenty-one of these fixed contacts, such as 124, 122, 123, 132', 133', and 134'. Continuing the following of the circuits from wire 121 and contact 122, it will be seen that connection is made to contact 124 and wire 125 by the contact-strip 1. The wire 125 is also connected to a fixed contact 126 under the reversing-switch 100. This contact 126 is in 80 electrical contact with another fixed contact 128, when the parts are in the position shown by means of the contact-plate 127. The contact 128 is connected to one terminal of the magnet-coil 130 by wire 129. The other terminal of this coil is connected to the switch 112 and wire 132 by wire 131. Following this wire 132 to the right hand of the drawing, it is seen that it is connected to another wire 133 and that this latter wire is 90 connected to the main at the point 134. It will thus be seen that by pushing the landing-button 23 a circuit has been established from the positive or + main through the double-wound magnet 45, floor-magnet 40, 100 floor-controller 120, reversing-switch magnet

130, and to the negative or - main. Current will now flow through the double-wound magnet 45; but as its coils 46' and 47 are wound in opposition, as pointed out before, the magnetic effect of coil 46' is neutralized 70 to such an extent that the magnet 45 is not sufficiently energized to attract its armature carrying the contact 49 against the action of the spring 52. The magnet-relay 40, however, will now be energized and will attract 75 its contact 57 until it makes contact with the core of the magnet-relay 40. As soon as this takes place a circuit is established by wire 48 and resistance 58 and contact 57 to the wire 26, establishing a parallel circuit to coil 47, 80 weakening said coil so that the coil 46' will now have sufficient strength to draw the contact 49 away from the contact 51 and by so doing cut off all current-supply to the push-buttons 23, 22, 21, and 20, and thus render 85 them inoperative.

At the same time that the foregoing operations have been taking place the magnet-coil 130 of the reversing-switch, as it is included in the circuit, as before pointed out, has been 90 sufficiently energized to raise its plunger 136, together with the contact-plate 137 and the insulating-plates 138 and 139, which are rigidly mounted thereon. The insulating-plates 138 and 139 carry contacts 143 and 145 and 95 147 and 146, respectively, so arranged as to be brought into contact with fixed contacts adjacent their path of travel. When the plunger 136 is raised by the magnet 130, the contacts 143 and 145 are raised out of engagement with the fixed contacts 142 and 144, respectively, while the contacts 147 and 146, which are carried on the insulating-piece 139, will make contact with the fixed contacts directly above them—that is, contact 100 147 will be brought into electrical contact with the contacts 148 and 149, and the contact 146 will be raised until it makes contact with the fixed contact 150. At the same time the contact-plate 137, which is also 105 mounted upon but insulated from the plunger 136, will be raised, breaking the connection between the two fixed contacts 140 and 141. Thus the coil 160 will be open-circuited at the contact 140. In a similar manner 110 if the coil 160 raises its plunger it will open the circuit to coil 130 at contact 128. Therefore it will be readily seen that as soon as one of the reversing-switch magnets raises its plunger it opens the circuit of the other reversing-switch magnet, thus providing an interlocking device and making it impossible to have both magnet-coils 160 and 130 operate at the same time. As soon as either of the plungers 151 or 136 has been raised to its 115 upper position a circuit will be established to the hoisting-motor, which will operate to raise or lower the car, as the case may be. The magnet-coil 130 having been energized 120 as soon as the button 23 was pushed and hav- 130

ing operated to raise its plunger 136 and the contacts carried thereon, as before pointed out, there will be established the following circuit to the motor: From the + main by 5 wire 153 and limit-switch 113 the current will pass through the blow-out coil 152 to contact 148. The contact 147 having been raised into contact with contacts 148 and 149, a connection is made between the positive line and the two wires 157 and 155. The 10 circuit by wire 155 will be pointed out later. As the contacts 145 and 144 have been disconnected by the raising of the plunger 136, current will flow by way of contacts 162 and 163 to the wire 158, wire 159, contact 146 to contact 150 and by wire 164 to the motor-brush 96. At the same time a parallel circuit has been made from wire 158 to brush 96 by way of resistance 98 and magnet-coil 97. Practically no current will flow this 20 way, however, as it contains considerable resistance, the current preferring the other path, which has practically no resistance. From brush 96 the circuit will continue 25 through the armature 94 to brush 95 and by wire 161 through the contacts 165 and 166 and by wire 167 to the starting resistance 80, through this resistance and by wire 168 through the series field 93 to wire 170 and 30 then to the - line. The shunt-field 92, as it is connected on one side to the + main by wire 157 whenever either reversing-switch is in its upward or raised position and as its other side is connected to the - main by 35 wire 170, will receive current at the full line potential.

The circuit established in wire 155 from the + main above referred to leads to the brake-magnet 61, through this magnet by 40 wire 156 to the - main. The magnet 61 will therefore be connected across the mains and will be energized to lift the plunger 62, which carries the weighted brake-shoe 63, thus leaving the friction-wheel 64, which is mounted 45 on the armature-shaft, free to revolve. The hoisting-motor now receives current which is limited by the resistance 80, and as the series and shunt fields are both excited and the brake is released the motor will now start to 50 revolve, and its motion will be transmitted through the hoisting mechanism and cables to the elevator-car.

The accelerating-magnet 50 has one terminal of its exciting-coil connected at 171 to the starting resistance 80, its other terminal being connected through the contacts 172 and 173 to the wire 155. It will be found by tracing the circuits that the coil of magnet 50 is in shunt with a circuit comprising the motor-armature and that portion of the resistance 80 between the wire 167 and the point 171. It might be well to mention here that the small contacts 172 and 173 are, by virtue of the small spring shown directly above them, normally held in contact with one another ex-

cept at such times as they are separated by the pull of the magnet 46, the operation of which will be explained later on. The excitation of the magnet 50, owing to the manner in which its terminals are connected, will be 70 gradual and depending on the counter electromotive force generated by the motor-armature, and consequently its speed. The various contacts 176, 177, 178, 179, and 180 are controlled by the magnet 50 and are so 75 placed with respect to the core of the magnet 50 as to operate consecutively. When the contact 176 is drawn into contact with the contact 181, that portion of the speed-controlling resistance 80 between the wire 167 80 and the contact 176 will be short-circuited. In a similar manner the contacts 177 and 178 operate to short-circuit further portions of the resistance 80. Contact 179 short-circuits a further portion of this resistance, together 85 with a part of the series field, while 180 connects the wire 167 by wire 135 to the - or negative main and by so doing short-circuits the remainder of the series field. By this time the resistance in series with the motor-armature, together with the series field, has been short-circuited and the motor will attain full speed. As soon as the contact 176 operated it opened a circuit between the contacts 174 and 175. The contact 175 is a fixed 90 one, while the contact 174 is mounted on but insulated from the contact 176 and will be carried out of engagement with the contact 175. The object of this will be shown further on. In a similar manner when the contact 180 was raised to its upper position by 95 the magnet 50 it carried the movable contact 54 out of engagement with the fixed contact 55. As long as these contacts are separated it will prevent a circuit being established between the wires 53 and 56, and as 56 is the feed-wire to the landing-buttons 23, 22, 21, and 20 it will be apparent that any manipulation of the landing-buttons after the motor has attained full speed will have no effect on 105 the system. While the action of the magnet 45, as before pointed out, operated to accomplish this same end, the contacts 55 and 54 are added to the system to further insure that after one landing-button has been pushed 110 and the system has gone through its cycle of operation the elevator-car will proceed to its destination without being in the meanwhile affected by the possible operation of the landing-buttons 20, 21, 22, and 23. 115

From the position of the car 10 and floor-controller 120, as shown on the drawing, the car is represented as being somewhere between the second and third landings, and since we have considered that the button 23 125 was operated the operation of the system would cause the car to descend. As the car approaches the landing at which the button has been pressed, the floor-controller 120, carrying its various contact-strips, as before 130

pointed out, being geared or otherwise connected to the elevator machinery will cause the strip 8 to be moved into engagement with the fixed contact or brush 123. Now the 5 contact-strip 8 is connected by wire to the strip 3, which in turn is in electrical connection with the brush or contact 134'. This contact 134' is connected by wire 182 to one terminal of the magnet 46, the other terminal 10 of this magnet being connected by wires 132 and 133 to the — main 135 at the point 134. Thus it will be seen that the magnet 46 is now placed in series with the floor-relay 40, resistance 58, and coil 46' of the magnet 45. 15 The magnet 46 will now operate to separate the contacts 172 and 173. This will at once deenergize the coil of magnet 50, allowing its contacts to drop back to their initial position. This operation will reinsert the resistance 80 and the series field 93 in the armature-circuit. By virtue of this the motor, if taking current from the line, will continue to revolve, but at a reduced speed. The next operation of the floor-controller 20 25 as it slowly revolves is to connect the contact-strip 7 with the fixed contact or brush 183. The contact-strip 7 being connected by wire to contact-strip 4 and by brush 183 to wire 185, a connection will thus 30 be established between wire 121 and wire 185. Now 185 is connected to one terminal of the magnet 65, whose other terminal is connected by wires 132 and 133 to the negative main 135. It will thus be seen that the magnets 46 and 65, each having one of their terminals connected to the wire 121 and their other terminals being both connected to the negative or — main at the point 134, are in parallel with each other. The magnet 65 will be 35 40 energized and will cause the movable contact 187 to engage the fixed contact 186, which contacts may be normally held out of engagement by a spring 188. As soon as 186 and 187 are in contact a circuit is closed 45 through the resistance 90 and the extra field 91 by placing them, as will be seen by an examination of the drawing, across the armature-brushes. Owing to an increase in field strength and to the fact that a portion of the 50 current to the motor-armature will be shunted away, the speed of the motor will be further reduced. The next operation of the floor-controller will be to connect the brush 133' to wire 189 by means of the contact-strips 65 and brush 184. The wire 189 is one terminal of the exciting-coil of magnet 16, the other terminal being connected at the point 1' to the wire 170, which leads to the negative main. The magnet 16 will now be 55 60 energized, so as to connect together the contacts 17 and 18, and this will connect the terminals of magnets 70 across the brushes of the motor-armature. The magnet 70 will receive current at the same potential as the motor-armature and will operate to close one 65

or more of its contacts, the effect of which would be to cut out more or less of the resistance 90 and by so doing still further reduce the speed of the motor. The next and final operation of the floor-controller 120 is 70 reached when the contact-strip 1 runs off the contact 122, thus breaking the circuit to the magnet 130 by wires 125 and 129. The magnet will be deenergized and the plunger 136 will drop to its initial position, and by so doing will cut off all current-supply from the motor-armature and connect the contacts 143 and 145 with 142 and 144, respectively. This operation will also break the circuit to the brake 60, allowing the plunger 62 to drop and apply the brake-shoe 63. At the same time the motor-armature is disconnected from the supply-main at the contact 147 and a circuit of comparatively low resistance comprising the resistance 98 and the coil of magnet 97 85 will be completed in series with the armature-terminals. The motor now acting as a generator will send current through this circuit, which will act as an electrodynamic brake and tend to bring the motor to rest. At the same time it will effect the operation of the relay comprising the magnet 97 and contacts 36 37 by causing said contacts 36 and 37 to become separated, and thus breaking the supply to the operating-circuits through the 95 wires 38 and 34 and preventing any current flowing to the operating-circuits until the motor has slowed down sufficiently to cause the current in magnet 97 to decrease until it allows the contacts 37 and 36 to come together again. The circuit to the floor-relay 40 having been broken, it will be deenergized and release the contact 57. The magnet-coil 46' will be deenergized and return the contact 49 to its original position, and the 100 circuits to the magnets 46, 65, 16, and 70 will also be broken, allowing them to return to their initial position ready for the next operation. 105 In reviewing the operation of slowing down 110 before the final stop it will be seen that the first operation was to replace the speed-controlling resistance and series field in the armature-circuit. This may cause one of two things to take place: First, if the motor is 115 taking current from the line it will cause a slight reduction of speed, owing to a strengthening of the motor-field and a reduction of current in the armature; second, if the motor is being driven by the load as a generator by placing the series field and resistance 80 in circuit it will tend to increase the speed of the motor as the magnetic field of the motor will be weakened and the armature-current reduced by the opposing effect of the series 120 winding. Almost immediately after this operation and before the motor has an opportunity to change its speed to any extent a resistance, together with an extra field, is thrown across the motor-armature. This will 125 130

further retard the rotation of the armature. The next step is to further increase the field strength by cutting out more or less of the resistance which is in series with the extra field.

5 Since the magnet controlling the cutting out of this resistance is placed directly across the armature-terminals, its action will depend upon the potential across the armature, and since this potential is governed by the speed 10 of the motor the magnet will cut out more or less of this resistance and by so doing regulate the amount by which the motor speed is reduced in accordance with the load. Thus it will be seen that there is a means for regulating the speed of the motor according to the load. The final step in stopping is to throw a circuit of comparatively low resistance across the armature-brushes, so as to utilize the dynamic action of the motor in still further slowing it down and at the same time to apply the brake and cut off all current from the operating and motor circuits and bring the elevator-car to rest.

If instead of pushing the button 23 one of 25 the other landing-buttons, such as 22, had been pushed, the operation would be similar to that which has just been pointed out, but would take place at another landing. If, however, the button 20 had been pushed, the 30 reversing-switch 100 would have been energized and the motor would run in a reverse direction, causing the car to travel upward. In this case the floor-controller would revolve in an opposite direction to that which it did 35 in the operation before described; but the cycle of operations when accelerating and slowing down would be the same. Should one of the buttons in the car be pushed, the operating-circuits would be somewhat different.

40 Assuming that the parts are in the position shown on the drawing and the button 15 be pressed, then, as before, a circuit will be established by wires 34 39, coil 46' of the magnet 45, and by wire 48, through the coil of magnet 44, and by wire 27, contacts 174 and 175, wire 28, to the left-hand side of car-button 15. Since the button 15 has been pressed, current will flow by wire 26 to the relay 40. The remainder of this circuit has already 45 been pointed out. The core of magnet 44 will be excited to operate the contact 29. This will place the magnet 44 and coil 46' of the magnet 45, together with a comparatively high resistance 71, across the supply-mains. The only points at which the circuit can be normally opened is either at the closed circuit-button 11 or at one of the door-contacts 30, 31, 32, or 33. Thus after the car has been brought to a full stop by the automatic operation of the floor-controller 120 the circuit through this safety-magnet 46' will be maintained, and this will prevent the operation of the landing-buttons before described until the landing-door has been 60 opened and closed again, thus restoring the

system to its original position. The circuit to the remaining car-buttons is broken at contacts 174 and 175 as soon as the motor has picked up speed. Since the current-feed to all of the buttons passes through the button 11, the operator in the car can, by pressing it, bring the car to a stop at once, regardless of its position in the hatchway. In a similar manner the limit-switches 110 and 112 may bring the car to rest should they be 70 caused to operate by the car running to the ends of its travel. The limit-switches 111 and 113 by opening the main line would also bring the car to rest. They may be set to be operated by the car if it runs beyond the 75 desired limits of its travel.

While automatic push-button electric elevators have been in use for some time for light duty service, it has been found difficult to adapt them to both light and heavy duties, 80 owing to the fact that if the floor-controller be set to stop the elevator-car at a certain landing while carrying a predetermined descending load as soon as the load is increased by an appreciable amount the same operation will stop the car below the landing, owing 85 to the greater momentum of the heavy load; but by using a system such as I have just described the braking effect is proportional to the load, the system operating to bring the 90 elevator-car to rest automatically, regardless of its load and speed, exactly at the desired landing without jar or shock.

The disclosure of my invention herein made is that of the preferred embodiment 95 thereof. I do not desire to be limited to the precise construction of details set forth in said disclosure, as the same may be varied in many particulars without departing from the spirit of my invention.

What I claim, and desire to secure by Letters Patent, is—

1. The combination with a motor, car and stations, of motor-controlling means connected to reduce the speed of the same before stopping at the limits of travel of said car and at any intermediate point and to vary such reduction of speed in accordance with the load whether descending or ascending.

2. The combination with a motor, car and stations, of automatic motor-controlling means connected to reduce the speed of the same before stopping at the limits of travel of said car and at any intermediate point and to vary such reduction of speed in accordance with the load whether descending or ascending.

3. The combination with a motor, car and stations, of motor-controlling device connected to the car and stations, and means for automatically stopping the car at any predetermined point intermediate the upper and lower limits of travel regardless of the load, direction of travel or speed of said car.

4. The combination with a motor, of a car

- and a plurality of controlling-stations, of motor-controlling means connected to reduce the speed of said motor before stopping at any floor-level and to vary such reduction of speed by an amount proportionate to the load. 5
5. The combination with a motor, of a car and a plurality of controlling-stations, of automatic motor-controlling means connected to reduce the speed of said motor before stopping at any floor-level and to vary such reduction of speed by an amount proportionate to the load. 10
6. The combination with a motor, of a car and a plurality of controlling-stations, of motor-controlling means connected to reduce the speed of said motor before stopping at any floor-level and to automatically vary such reduction of speed by an amount proportionate to the load. 15
- 20 7. The combination with a motor, car and a station, of means for excluding control of said car after being started from said station, and means for automatically stopping said car gradually regardless of its load or the skill 25 of the operator, at any desired floor-level.
8. The combination with a motor, car and a station of means for excluding control of said car after being started from said station, and means for automatically stopping said 30 car gradually regardless of its load or the skill of the operator or direction of travel at any desired floor-level.
9. The combination with a motor, car and a station of means for excluding control of 35 said car after being started from said station, and means for automatically stopping said car gradually regardless of its load or the skill of the operator, direction of travel or speed.
10. The combination of a car and motor, 40 with push-buttons, one at each floor or station, means for controlling said motor from one of said push-buttons to the exclusion of the others, and means for automatically reducing the speed of said motor before stopping and to vary such reduction of speed in accordance with the load. 45
11. The combination of a car and motor, with switches at a plurality of floors or stations, means for controlling said motor from 50 any one of said stations to the exclusion of the other stations, and automatic means for stopping the car at the same point with varying loads.
12. The combination of a car and its motor, with switches at various landings or stations, means for controlling said motor from any one of said stations, to the exclusion of the switches at the other stations, and means for automatically reducing the speed of said 60 motor as the car reaches predetermined points in its traverse, and vary such reduction of speed in accordance with the load. 65
13. In an elevator system, the combination with a motor and car, of switches at the various floors or landings, switches on the car, electrical motor-controlling means for preventing subsequent control of the motor from a floor or station after it has been operated from the car, and means for gradually stopping the car at a predetermined point by automatically changing the speed and varying such change of speed in proportion to the duty. 70
14. The combination of a car and its motor, with circuits and connections for an automatic push-button-controlled elevator system, and means for automatically stopping the car at the same point with varying loads. 75
15. The combination of a car and its motor, with motor-controlling means for automatically stopping said car at the limits of its travel or at any predetermined intermediate point regardless of its load and the skill of the operator. 80
16. In an elevator system, the combination of a car and its motor, with motor-controlling means for automatically reducing the speed of the same, to vary such speed in accordance with the load whether ascending or descending and stopping said car at any predetermined point in its travel. 85
17. In an elevator system, the combination with a car and its motor, of motor-controlling means for automatically stopping said car at any predetermined point in the travel of said car regardless of the load, direction of travel or speed or the skill of the operator. 95
18. The combination with a car and its motor, of automatic motor-controlling means for gradually stopping the car at the limits of its travel or at any intermediate point regardless of its load whether ascending or descending. 100
19. The combination with a car and its motor, of motor-controlling means for automatically reducing the speed of said motor in proportion to the load and stopping the same at the limits of the travel of said car or at any intermediate point whether the car is ascending or descending. 105
20. The combination of a car and its motor, with automatic motor-controlling means connected to reduce the speed of said motor at any predetermined point in the traverse of said car, and automatic means operating with said motor-controlling means for proportioning such reduction of speed to the load whether the car is ascending or descending. 115
21. The combination of a car and its motor, with motor-controlling means connected to reduce the speed of said motor at any predetermined point in the traverse of said car, and automatic means operating with said motor-controlling means for proportioning such reduction of speed to the load whether the car is ascending or descending. 120
22. The combination of a car and its motor, with motor-controlling means connected to automatically reduce the speed of said motor 125

5 tor and thus gradually stopping the same at any predetermined point in the traverse of said car, and means operating in conjunction with said motor-controlling means for varying such reduction of speed by an amount proportional to the load whether the car is ascending or descending.

23. The combination with the car and its motor, of means for introducing variable resistance in series and in shunt with the armature at the limits of the traverse of said car or at any intermediate point, and means for varying said resistance automatically in accordance with the speed of the motor.

5 24. In an elevator system, the combination with a car and its motor, of motor-controlling means connected to change the speed of the motor at the limits of traverse of said car or at any predetermined intermediate point, and means operating in conjunction with said motor-controlling means for regulating said reduction of speed in accordance with the potential developed by the armature after the initial change of speed at a predetermined point.

30 25. The combination with the car and its motor, of motor-controlling means connected to change the speed of the motor at the limits of traverse of said car or at any intermediate point, and means operating in conjunction with said motor-controlling means for regulating said change of speed in accordance with the load whether ascending or descending.

35 26. In an elevator system, the combination with the car and its motor, of motor-controlling means connected to be governed by the load whether ascending or descending for reducing the speed of said car at the limits 40 of its travel and at any predetermined intermediate point.

45 27. The combination with the motor and car, of means connected to the motor and a station for starting the motor in either direction, and controlling means connected to operate automatically to reduce the speed of the motor in proportion to the load whether ascending or descending at the limits of the travel of said car or at any predetermined point between said limits.

50 28. In a hoist, the combination with the cage and its motor, of motor-controlling means connected to automatically reduce the speed of the cage at the ends of its travel or at any predetermined intermediate point and to vary such reduction of speed in proportion to the load whether ascending or descending.

55 29. In an electric elevator system, the combination with an electric motor, of a car mechanically connected to the same, means connected to start and stop said motor from any landing, and motor-controlling means connected to automatically reduce the speed of said motor before stopping at the limits of travel of said car or at any predetermined

intermediate point and to vary such reduction of speed by an amount determined by the load.

30. In a push-button elevator system, the combination of a car and its motor, means connected to control the starting, stopping and reversing of said motor from any landing or from the car, and motor-controlling means connected to automatically reduce the speed of the motor before stopping and to proportion such reduction of speed by an amount determined by the load.

70 31. In an elevator system, the combination with a car and its motor, of motor-controlling means connected to reduce the speed of the motor at the limits of travel of the car or at any predetermined intermediate point in the traverse of the car and to vary such reduction of speed inversely to the load whether ascending or descending.

80 32. The combination with a car, of an electric motor for operating same, electric circuits and connections of an automatic push-button-controlled elevator system, means operating in conjunction therewith for automatically stopping said car substantially level with any predetermined floor without shock or jar regardless of the load whether ascending or descending, direction of travel or speed of the said car.

85 33. In a push-button-controlled elevator system, the combination of a car and its motor, with electrical circuits and connections for operating same, a floor-controller, a resistance for the armature, an electromagnet 100 for gradually cutting said resistance out of circuit with said armature, normally closed contacts in series with said electromagnet, a magnet adjacent said contacts and electrically connected to said floor-controller, all so constructed and arranged that at a predetermined point said floor-controller will close the circuit to the magnet last mentioned thus breaking the circuit through the first-mentioned magnet.

110 34. In apparatus for controlling elevators, the combination of a car, motor and stations, with circuits and connections of an automatic push-button-controlled system, electromagnetic means for gradually short-circuiting resistance and a series field from in circuit with the armature of the motor, contacts adjacent said means adapted to be opened thereby just before the said field is entirely short-circuited thus breaking the circuit to the floor push-buttons.

115 35. In an electric elevator system, the combination of a car and motor, with circuits and connections of an automatic push-button-controlled system, resistance in series with 125 the armature, electromagnetic means for short-circuiting said resistance, contacts adjacent said means and electrically connected to push-buttons in the said car, all so constructed and arranged that at a time just be- 130

- fore any of said resistance is short-circuited the said contacts are separated, thus breaking the circuit to said push-buttons on the car.
36. In a motor-controlling apparatus, the combination with a motor, of a normally open variable-resistance circuit in shunt to the armature, a floor-controller, means electrically connected with said floor-controller for closing said normally open circuit, and means for closing a circuit to said floor-controller.
37. In a motor-controlling apparatus, the combination with a motor, of a normally open variable-resistance circuit in shunt to the armature, a magnet for closing said circuit, electromagnetic means for short-circuiting said resistance, said means being in a normally open shunt-circuit to the armature, and means for closing said last-mentioned circuit.
38. In a motor-controlling apparatus, the combination with a motor, of an extra field and variable resistance in series with each other but in shunt to the armature, the circuit of said field and resistance being normally open, electromagnetic means for short-circuiting said resistance, said means being in a normally open circuit, magnets for closing said normally open circuits, a floor-controller electrically connected to said magnets at predetermined points in its operation, and means for closing the main circuit to said floor-controller.
39. In a push-button elevator system, the combination with a car and its motor, of means comprising a floor-controller for gaining exclusive control of said car, an extra field and variable resistance, means connected with said controller for throwing said field and resistance in shunt to the armature, electromagnetic means for short-circuiting said resistance, means operated from the controller after the field and resistance have been thrown in shunt to the armature for throwing said electromagnetic means in shunt to the armature-terminals.
40. In a push-button elevator system, the combination with a car and its motor, of means including a floor-controller for gaining exclusive control of said car, means comprising an extra field and variable resistance in circuit therewith for gradually stopping said motor, electromagnetic means electrically connected with said controller for throwing said field in shunt with the armature, means in a normally open circuit for varying said resistance in accordance with the speed of the armature, and means connected with the controller for closing the last-mentioned circuit.
41. In a push-button elevator system, the combination with a car and its motor, of means comprising a floor-controller for gaining exclusive control of said car, means for gradually stopping the car, said means comprising an extra field, a variable resistance in series therewith, an electromagnet connected electrically with the floor-controller and adapted to close the circuit of said field and resistance and throw the same in shunt with the armature, an electromagnet for gradually short-circuiting the said resistance, an electromagnet also connected to said floor-controller and adapted to close the circuit of said resistance-controlling magnet and throw the same in shunt to the armature.
42. The combination with a motor, of an operating-circuit therefor, a relay, and automatic means for operating said relay upon interruption of the main-line circuit to the motor to effect an opening of said operating-circuit.
43. In a push-button elevator system, the combination of a car, with an electric motor to operate same, circuits and connections for gaining exclusive control of said car, an electromagnet and resistance, means for automatically placing said electromagnet in series with said armature and energizing said electromagnet, a main line for supplying current to said motor, a circuit in shunt to said motor, normally closed contacts in said shunt-circuit and adjacent said electromagnet, all so constructed and arranged that when said contacts are separated to break said shunt-circuit all the push-button-controlling circuits and connections are restored to normal.
44. In a push-button elevator, the combination with an electric motor, a car operated thereby, circuits and connections for gaining exclusive control of said car, a magnet, a resistance, means for placing said magnet and resistance in series with the armature, a main-line for supplying current to the motor, a circuit in shunt to the motor, means in said shunt-circuit adapted to be operated upon by said magnet when sufficiently energized to restore the circuits and connections of the push-button system to normal.
45. In a push-button elevator system, the combination with an electric motor, a car operated thereby, circuits and connections for gaining exclusive control of said car, a magnet, means for placing said magnet in series with the armature, a main line for supplying current to the motor, a circuit in shunt thereto, means in said shunt-circuit adapted to be operated upon by said magnet when sufficiently energized to restore the circuits and connections of the push-button system to normal.
- In witness whereof I have hereunto signed my name in the presence of two subscribing witnesses.
- JOHN D. IHLDER.
- Witnesses:
- CHAS. H. LANGE,
FRANK T. BROWN.
